(57) **CLAIM**

The ornamental design for a mixing console, as shown and described.

DESCRIPTION

FIG. 1 is a perspective view of a mixing console showing our new design;

FIG. 2 is a top plan view thereof;

FIG. 3 is a side elevational view of one side thereof;

FIG. 4 is a side elevational view of the opposite side thereof;

FIG. 5 is a front elevational view thereof;

FIG. 6 is a rear elevational view thereof; and,

FIG. 7 is a bottom plan view thereof.

The broken line showings of the rectangular and circular controls and indicators are for illustrative purposes only and form no part of the claimed design.

1 Claim, 5 Drawing Sheets
